UNITED STATES PATENT OFFICE.

TOYOHARU TERAOKA, OF LOS ANGELES, CALIFORNIA.

ADDING-MACHINE.

1,036,375.

Specification of Letters Patent. Patented Aug. 20, 1912.

Application filed September 5, 1911. Serial No. 647,772.

To all whom it may concern:

Be it known that I, TOYOHARU TERAOKA, a subject of the Emperor of Japan, residing at Los Angeles, in the county of Los Angeles and State of California, have invented a new and useful Adding-Machine, of which the following is a specification.

This invention relates to a machine which is particularly intended for adding figures or numbers, although it may be used for subtraction as well as for addition.

The main object of the invention is to provide an adding machine of extremely simple construction, so as to reduce the size, weight and cost of the machine to a minimum.

A further object of the invention is to provide an adding machine in which the number of keys required for a set of nine figures is reduced so that any number in the set of nine figures can be selected by the use of the fingers of one hand. In this connection the invention is of particular value in that it provides for a selection of the numbers by touch rather than by sight, thereby greatly expediting the selective operation and reducing the chance of error.

A further object of the invention is to provide in an adding machine, means for performing the registering and totalizing operations simultaneously or concurrently with the selective operations, thereby avoiding the use of a registering lever or handle and the time and expense incident to the use of such a handle.

A further object of the invention is to provide convenient and simple means for changing the machine at will from adding to subtracting operation.

Other objects of the invention will appear hereinafter.

The accompanying drawings illustrate an embodiment of the invention, and referring thereto:

Figure 1 is a plan of the machine, with parts broken away. Fig. 2 is an end elevation, partly broken away to show the working parts of the machine. Fig. 3 is a plan of one of the dials. Fig. 4 is a plan of a portion of the case with two of the dials underlying the same, showing the relative position of the dials. Fig. 5 is an end elevation of a portion of the registering devices. Fig. 6 is a section on line x^6-x^6 in Fig. 5. Fig. 7 is a side elevation of parts shown in Fig. 6. Fig. 8 is a plan of one of

the operating wheels and ratchet device for a registering device. Fig. 9 is a side elevation of one of the sets of clearing gears. Fig. 10 is an inverted plan of the operated clearing gear. Fig. 11 is a side elevation of the operating clearing gear.

The machine comprises a case or box 1 in which the working parts are inclosed, said box having in its top or cover 2, a series of openings 3 through which are exposed the numbers 4 on the dials 5. Each dial 5 is carried by a vertical shaft 6 journaled in suitable bearings 7. A sleeve or tubular shaft 9 is mounted to slide vertically on the shaft 6, but is splined thereto as shown at 9', so as to rotate therewith, said sleeve 9 carrying two bevel gears 10 and 11 for alternatively engaging with a bevel wheel 12 at opposite sides of the center of said wheel 12 to transmit to the sleeve 9 and the dial in a forward or in a reverse direction as may be desired, the rotation of the bevel wheel 12. Bevel wheels 12 are rotatably mounted on a fixed shaft 17 and each of said wheels is operated by key-controlled mechanism hereinafter described, said mechanism operating on a ratchet wheel 14 rigidly connected to the bevel wheel 12 and turning therewith. Two operating ratchet devices are provided for each ratchet wheel 14, said ratchet devices comprising two arms 15, 16, swingingly mounted on the shaft 17 carrying the bevel wheel 12, said arms 15 and 16 carrying spring pawls 18 and 19 slidably mounted in said arms and engaging respectively with the ratchet teeth or wheel 14 on opposite sides of the center of said wheel. Springs 20 and 21 connected to the respective arms 15 and 16 tend to draw the same downwardly. The respective ratchet wheels and the bevel wheels 12 connected thereto are mounted in parallelism and coaxially on the shaft 17, being spaced apart sufficiently to provide for operation of the pawl means and dial operating shafts between said wheels, said dial operating shafts being arranged in parallelism and alternating with the ratchet devices, the construction thus provided being extremely compact and providing for operation of dials for a large number of denominations in limited space.

A set of controlling devices including keys and one of the ratchet mechanisms above described is provided for each set of nine figures, each set of keys comprising four keys 24, corresponding respectively

- to the first four digits and a key 25 corresponding to the numeral 5, said key 25 also being operated concurrently with any one of the other keys in the set 5 to make up the remaining nine digits. The zero digit requires no key. Said keys are formed as heads or buttons on key levers 28 and 29 pivoted at 30 and 31 in the case 1, said heads or buttons being numbered, as 10 shown directly above the respective keys in Fig. 2. These five keys for each set are preferably arranged in a curve, as shown in Fig. 1, so as to accommodate more readily the position of the fingers of the hand. 15 Each key lever 28 is normally drawn by a spring 33 so that the key end is raised and the inner end of the lever is held down. The inner end of each of the levers 28 extends beneath a pin 22 on the arm 15 of the 20 corresponding ratchet mechanism limiting the downward movement of the arm. Each key lever 29 is connected at its inner end by a link 35 with the arm 16 of the corresponding ratchet mechanism so that the spring 21 25 for said arm 16 holds the key lever 29 in position with its key 25 raised and said key lever limits the downward movement of the arm 16.

Means are provided for shifting the tubular shaft or sleeve 9 to bring one or the other of the bevel wheels 10 or 11 into engagement with the bevel wheel 12. For this purpose a cam 37 is rotatably mounted on the shaft 38 provided with operating 30 handle 39 and engaging with shoulders 40 and 41 on a sleeve 46 having an arm 46' engaging between shoulders 47 on said sleeve 9 to move the sleeve 9 with the bevel wheels carried thereby, upwardly or downwardly, the upper bevel wheel 10 being in engagement with the bevel wheel 12 for forward driving of the dial when the sleeve 9 is depressed and when the sleeve 9 is raised, the bevel wheel 11 is 40 brought into engagement with the wheel 12 and the bevel wheel 10 is removed from such engagement so as to connect the dial for reverse operation in subtraction.

Any suitable carrying means may be used 50 for carrying to the next higher ratchet mechanism or registering device when any one of the registering devices passes the number 10. For this purpose each of the shafts 6 may be provided with an arm 43 55 adapted to engage between the teeth of a wheel 44 mounted and gearing with a gear wheel 45 on the shaft 6 of the next higher registering device.

Means are provided for clearing the registering device for returning the same to zero when desired, said means consisting of 60 a shaft 48 extending transversely across the case beneath all of the series of shafts 6 and provided with an operating handle 49, said 65 shaft 48 carrying mutilated gears 50 adapt-

ed to coöperate with bevel gears 51 on the lower ends of the respective shafts 6.

The top of the case may be marked with bands or lines indicated at 52, indicating the correspondence of each rank of keys with 70 one of the side openings 3 in the case for exposing the numbers on the dial controlled by said rank of keys.

The operation is as follows: Normally, the clearing device is positioned with the break or mutilation in the gears 50 opposite the respective bevel gears 51, so as to leave said bevel gears free for rotation under the operation of the key devices. All of the keys are raised by operation of the respective 75 springs aforesaid, and their inner ends are depressed so that the ratchet arms 15 and 16 are in lowermost position. The spring pawls 18 and 19 on said ratchet arms are held in engagement with the ratchet wheel 80 14 on opposite sides of the center thereof, and hold said wheel and the registering devices connected thereto from accidental rotation. Assuming now that a number in the unit column or section is to be added, 85 the operator places his hand with the finger resting on or above the lowermost set of keys and depresses the key or keys for selecting the required unit. If the unit desired is 1, 2, 3, or 4, the operator simply 90 presses down the finger which is directly over said key. In this operation the corresponding key lever 28 is depressed and the inner end of said key lever is raised, causing the corresponding arm 15 to be 95 raised, the spring ratchet or pawl 18 on said arm slipping over the teeth of the ratchet wheel 14 in this movement, the other pawl 19 engaging with the ratchet teeth of wheel 14, so that said wheel is prevented from rotation in this operation. Then, when the operator releases the operated key 24, the key lever 28 is restored to normal position by the operation of its spring 33 and the ratchet wheel 15 is drawn down by its 100 spring 20, causing the pawl 18 which is in engagement with the ratchet wheel 14, to 105 push the ratchet wheel around a distance corresponding to the amount which the arm 15 has been lifted.

The pivots 30 for the key levers 24 are so arranged that the distances through which the inner ends of the key levers are lifted by the operation of their respective keys are variant, according to the numeral represented by the key, the inner end of the key lever 1 moving through a space sufficient to cause operation of the ratchet wheel 14 through the distance of one tooth in the descent of the lever, the key lever for the numeral 2 moving sufficiently at its inner end to cause operation of the ratchet wheel through the space of two teeth, etc. If the numeral 5 is to be counted, the key 25 is depressed and the inner or rear end of 110

the key lever 25 is thereby raised and by engagement of the spring pawl 19 with the ratchet wheel 14, pushes the ratchet wheel around a distance of five teeth, and in the 5 return movement of the key lever 29 under the action of spring 21, the spring pawl 19 slips over the ratchet teeth on wheel 14, the wheel 14 being held from back movement in this operation by the engagement there- 10 with of the spring pawl 18. Thus, each spring pawl serves to hold the ratchet wheel stationary during the operative stroke of the other spring pawl and the spring pawl 18 operates on the back stroke, whereas the 15 spring pawl 19 operates on the forward stroke. By reason of this different opera- 20 tion of the two pawls respectively on the backward and forward strokes, it is possible to operate the key 25 concurrently with any one of the keys 24 and to thereby count or add numerals from 6 to 9 inclusive. Thus, for numeral 6 the key 25 for numeral 5 and the key 24 for numeral 1 will be simultaneously depressed. As the said key 25 is 25 depressed it pushes the ratchet wheel 14 around the space of five teeth and simultaneously the depression of the key 24 raises the pawl device 18 a space of one tooth, said pawl device slipping over the ratchet teeth 30 of wheel 14. Then as both keys are released the return of the operated key lever 28 to normal position operating through pawl 18, advances the ratchet wheel 14 another tooth and in this return movement the pawl de- 35 vice 19 slips over the teeth of the ratchet wheel. By this operation the wheel 14 was first advanced five teeth, by the operation of the key 25 and then one tooth by the operation of the key 24, the operation being 40 successive, although the selection by the finger was simultaneous. In the same manner numbers 7, 8 and 9 may be added by simultaneous depression of keys 24 for numerals 2, 3 and 4 along with the key 25. 45 The lever wheel 10 being normally engaged with the wheel 14 transmits to the shaft 6 and the dial 5 thereon, the rotary motion imparted by the operations above described and advances the dial one number for each 50 ratchet operation for the wheel 14 through a space of one tooth, the numbers on the dial being brought beneath the openings 3 in the top of the case so that the total may be read through said openings and as any dial passes 55 the zero or ten mark, it automatically carries it to the next higher dial by operation of the arm 43 and of gears 44 and 45. By providing the intermediate gear between the operating arm 43 and the gear 45 on the 60 next higher dial, all of the dials are enabled to turn in the same direction, but the invention is not limited to such construction as the carrying mechanism may be variously arranged without departing from the invention. 65 In case it is desired to clear the reg- ister or return all the dials to zero, the clear- 70 ing shaft 48 is given only one rotation by means of the handle 49, causing the multi- lated gears 50 to engage with the bevel gears 51 on the respective shafts 6, rotating 75 all of said shafts until the dials are returned to zero.

In case it is desired to subtract any number from the total already enumerated on the registering device, it is only necessary 75 to turn the shaft 38 by means of its handle 39 so as to cause the cam 37 to raise the tubular shaft 9, so as to bring the lower bevel wheel 11 thereon into engagement with the bevel wheel 12 and remove the bevel wheel 10 80 from such engagement. The forward ro- 85 tation of the bevel wheel 12 through the ratchet wheel 14 and the operating devices therefor, under the selective operation of the keys serves to rotate the shaft 6 in the 85 opposite direction to that which takes place in the operations above described so that the dials are turned back and the number selected by the keys is subtracted from the 90 previous registration.

The several ranks of keys being arranged in curved order as shown, to conform to the natural position of the operator's fingers, it is not necessary for the operator to shift the position of the hand laterally, but simply 95 move it up or down according to the de- 100 nomination desired, and the whole key board is within range of the fingers without any shifting either laterally or vertically. This enables the operator to operate the 100 keys by the touch system as distinguished from the sight system, the touch system being not only more rapid but less liable to error.

What I claim is:

1. In an adding machine, a plurality of registering dials for different denomina- 105 tions, a series of coaxially mounted ratchet wheels connected to operate the respective dials, mechanism for operating each dial on completion of rotation of the dial of the next lower denomination, a plurality of ranks of keys, one rank for each ratchet device, and each rank of keys comprising five keys, 110 levers operated respectively by four of said keys, a pawl device operated by said levers and engaging the corresponding ratchet wheel at one side thereof, a lever operated by the fifth key in each rank, a pawl device operated by said last named lever and en- 115 gaging with the corresponding ratchet wheel on the opposite side from said first named pawl, said levers being mounted to provide for variant movements of the ratchet wheel in one direction by movement of the said four keys in one direction and to provide for a greater movement of the ratchet wheel in the opposite direction by movement of the 120 said fifth key in the opposite direction.

2. An adding machine comprising a series 125

- of dials for different denominations, a series of coaxially mounted ratchet wheels, means connecting each ratchet wheel to a corresponding dial, two pawls pivotally mounted coaxially with and adjacent to each ratchet wheel and engaging with the ratchet wheel at opposite sides thereof, a rank of keys for each ratchet wheel, a plurality of levers connected to be operated by the respective keys 5 in each rank, four of said levers engaging with one of said pawls and mounted to produce variant movement of said pawls by the return operation of the corresponding keys, and the fifth lever for each rank of keys 10 being connected to operate the other of said pawls on the forward movement of the corresponding key.
3. An adding machine comprising a series of dials for different denominations, shafts 20 connected with the respective dials and extending in parallelism, carrying devices connected with the respective dials for moving each dial on completion of rotation of the dial of the next lower denomination, a series 25 of ratchet wheels mounted to rotate coaxially, said dial shafts extending between said ratchet wheels, a bevel wheel carried by each ratchet wheel, a sleeve mounted to slide on each of said dial shafts and connected to 30 said dial shafts to turn therewith, two bevel wheels on each sleeve for engagement alternatively with said bevel wheel on the corresponding ratchet wheel, means for moving said sleeve to cause engagement of either of 35 the bevel wheels thereon with the bevel
- wheel on the ratchet wheel, pawl devices engaging with the respective ratchet wheels, and a plurality of key levers adapted to operate each of said pawl devices through variant distances. 40
4. An adding machine comprising a series of dials for different denominations, a series of coaxially mounted ratchet wheels, means connecting each ratchet wheel to a corresponding dial, two pawls pivotally mounted 45 coaxially with and adjacent to each ratchet wheel and engaging with the ratchet wheel at opposite sides thereof, a rank of keys for each ratchet wheel, and a plurality of levers connected to be operated by the respective 50 keys in each rank, four of said levers engaging with one of said pawls and mounted to produce variant movement of said pawls by the return operation of the corresponding 55 keys, and the fifth lever for each rank of keys being connected to operate the other of said pawls on the forward movement of the corresponding key, the pivots for said levers being arranged at variant distances relatively to the corresponding 60 keys and pawl devices so as to provide for variant strokes of the pawl devices with uniform stroke of the keys. 65

In testimony whereof, I have hereunto set my hand at Los Angeles, California this 26th day of August, 1911.

TOYOHARU TERAOKA.
